IRONING TABLE TOP

Les W. Place, Minneapolis, Minn., assignor to the
J. R. Clark Company, Minneapolis, Minn., a
corporation

Application November 24, 1939, Serial No. 305,921

1 Claim. (Cl. 38—137)

My invention relates to ironing table tops and has for its object to provide an ironing table top embodying a wooden base with a metallic sheathing overlying the top of said base either directly or with insulating material between the wooden sheathing and said top of the base.

It is an object of my invention to provide an ironing table top having in conjunction with a metal contacting upper surface portion a wooden base so constructed and united with the ironing table top as to prevent warping from shrinkage or any other cause, to effect diffusion of heat from the iron over the metallic top and to provide additional safety against fire hazards.

It is a further object of my invention to provide reenforcement transversely of the wood base of the ironing table top by means of transverse steel cleats of any desired shape, which cleats also may be the securing means for the leg supports of the ironing table top, said leg supports being of any desired construction.

It is a further object of my invention to provide in conjunction with the board itself a suitable wiring arrangement such that the heating elements employed to heat the metallic sheet forming the contacting upper surface of the ironing table top may be plugged in from a source of electrical current supply and the electric iron may be plugged in directly at the ironing table top in connection with switching means for controlling the circuit to the iron and to the heating means.

The full objects and advantages of my invention will appear in connection with the detailed description thereof, and its novel features by which the above indicated advantages are attained are particularly pointed out in the appended claim, it being understood that the invention is not limited to the specific showing and detailed description given, but may be varied within the scope of the claim.

In the drawing illustrating applications of my invention in some desirable forms,

Fig. 1 is a top plan view of a table top embodying my invention with some parts broken away and in section.

Fig. 2 is an underside plan view of my table top.

Fig. 3 is an underside plan view of the table top showing a form of development of the wood base member to prevent warping.

Fig. 4 is a greatly enlarged transverse sectional view taken on line 4—4 of Fig. 1 with parts broken away.

Fig. 5 is a partial sectional view similar to the

showing of Fig. 4 showing how the metallic top sheathing can be employed either directly in contact with the wood base member or spaced therefrom for the reception of insulating material.

As illustrated, a wooden base member 10 is employed of a suitable thickness to give body and sufficient rigidity to the ironing table top. This base member may be of any desired type of lumber and preferably will be treated with well-known chemical substances to render it fire resistant. As clearly shown in Figs. 3 and 5, the wooden base member 10 may be provided with a multiplicity of longitudinal grooves 11 which will be carried through the board 10 to a point indicated at 12, which is spaced from the adjacent surface of the board 10. These grooves are shown as rectangular slits such as would be conveniently obtained by saw cuts, but the form of the grooves may be varied as desired so long as they produce the desired effect of preventing warping from expansion or contraction, and at the same time give to the surface of the board when employed, as in Fig. 5, a certain amount of yield under the iron, which is a desirable condition in connection with the ironing operation. Although the grooves 11 are shown as in Fig. 3 and 5 in conjunction with the metallic covering 13 applied directly to the wooden base 10, it will be obvious that the grooves where desired may be used with the solid base 10, as shown in Fig. 4; and likewise that the solid base 10 may be employed in conjunction with the directly applied metal top covering, as in Fig. 5.

The wooden base member 10 is formed with a groove 14 extending around the outer margins thereof as shown in Fig. 5, and the metal top member 13 is provided with a curved lip 15 which has its edge 16 seated in the groove 14, thus at the same time firmly securing the metal covering 13 upon the base member 10 and giving an ornamental beaded finish to the edge of the ironing table top.

As shown in Fig. 4, a sheet metal cover member 17 is provided with rectangularly disposed walls 18 and a rectangular bottom flange 19 which takes over the bottom of the wooden base member 10, securing the sheet metal member 17 to said base member. It will be clear, however, that the sheet metal member 17 can, if desired, be secured to the wooden base member 10 in the same manner as the sheet metal member 13 is shown secured to the base member 10 in Fig. 5. As clearly shown, the member 17 is spaced from wooden backing piece 10 as indicated at 20, Fig.

4. Within this space is compressed a mass of insulating material 21. This material may be any insulating material, but in practice will preferably be a non-combustible material such as rock wool, and will be suitably compressed within the space 20 so as to make a compact layer within that space. Such a layer of insulating material will effectively restrain passage of heat from the sheet metal cover 17 through to the wooden base member 10 when the construction is used for ironing.

This construction also lends itself very effectively to the production of a metal top ironing table top which is itself heated. There are certain advantages in ironing which flow from the use of a heated metallic table top. Different forms of ironing table tops intended to accomplish this purpose have been suggested. These forms are either too heavy, too expensive, or both, to be practical. My construction by employing heating wires in contact with the metal cover 17 and embedded in the mass of insulating material 21 provides the desired heated ironing table top effectively in a light and easily handled construction and in a construction which can be manufactured at a reasonable cost. As shown, resistance wires 22 are embedded in the insulation 21 in substantial contact with the under surface of the sheet metal cover 17. These wires, as indicated at 23, 24, 25 and 26 by dotted lines in Fig. 1, run from a plug-in device 27, Figs. 1 and 2, which receives current from an electric plug and line wires in a usual way.

As shown in Fig. 4, the resistance or heating elements 22 may be encased in a channel member 31 secured to the sheet metal member 17 with incombustible insulating material 32 within the channel and about the heating element 22. In some cases this may be desirable to further protect the wooden base member 10 from the heat generated by the heating wires 22, although extensive experimentation has shown that such an additional safeguard actually is not required. Also, the casing 31 may, if desired, be formed of some heat insulating material such as Bakelite.

For adapting my improved ironing table top to be used with electrical heating, I apply to the end of the wooden support a switching member 32, Figs. 1 and 2, which embodies the plug-in socket 27 and a second plug-in socket 33 adapted to receive the plug of the electric flatiron cord, and a central switch device 34 of known construction, for controlling the flow of current.

In either form of ironing table top, that is when the sheet metal cover rests directly upon the wooden base member, as in Fig. 5, or when the sheet metal cover is spaced therefrom with

intervening heat insulating material, as in Fig. 4, a series of transverse metallic bars 51 will be secured across the bottom of the base member 10, as clearly shown in Fig. 2. These bars may 5 be of any desired shape, preferably with one or more outwardly extended ribs, such as would be true with U-bars and angle-iron bars. Any suitable number of these bars may be employed sufficient to give the necessary transverse stiffness, and the bars may be additionally employed 10 as a means for securing the customary supporting legs to the ironing table top.

The advantages of my invention have been quite fully pointed out in the description heretofore given. A primary and principal advantage resides in the fact that a metallic cover is combined with a wooden supporting base member in such manner that a relatively light and strong structure is obtained in which absorption of moisture which always takes place to a considerable degree with a wooden ironing table top is avoided and unyielding smoothness of ironing surface accompanied by a considerable degree of resiliency to that surface is obtained.

Further, the employment of a sheet metal cover for the ironing table top in combination with the wood supporting base makes possible the use of relatively thin sheet metal for this covering with sufficient strength and rigidity, and by spacing the sheet metal from the wooden base 25 and filling the space with heat insulating material, a practical and efficient way of providing means for heating the metal cover to the table top is provided.

35 I claim:

An ironing table top comprising a base member formed of a wooden board of substantial thickness and with transverse reenforcing means adapted to connect supporting legs to the table 40 top, the board being formed with a pair of rounded beads extending about all margins of the board and uniting at the center of the edge of the board to form a continuous V-shaped groove, a sheet metal cover resting upon the 45 wooden base member and completely covering its top, said cover member having a continuous flange shaped to extend about the entire ironing table top and curved to fit the curve of the top bead and having its edge seated in and concealed 50 by said central V-shaped groove, whereby the metallic member is united with the base member and is held thereon without screws or other fastening devices so as to give an appearance of complete unity between the wooden base member 55 and the metal top thereon.
